APPLICATOR

Emory W. Worthington, Chicago, Ill.

Application May 10, 1943, Serial No. 486,390

2 Claims. (Cl. 15—137)

The present invention relates to improvements in applicator type containers as well as to a novel form of applicator therefor. Devices of the present invention are especially suited to the application of plastic or viscous materials such as lip rouge, unguents, etc., to soft yielding surfaces such as the lips or other part of the body.

Generally stated, the object of the present invention is to provide a device of the type indicated embodying a novel arrangement for presenting the material for easy application without excessive rubbing but which at the same time retains the material against smearing and daubing.

More specifically, it is an object of the invention to provide such a device employing an applicator surface of intagliated or pocketed form and throughout which are distributed a plurality of small openings through which the material is extruded, whereby the material is not only presented at distributed points (by the several openings) for application, but in addition the intagliations or pockets pick up the excess material as the applicator is wiped across the surface to which it is being applied and present it, or represent it, for application, while at the same time confining it in a lateral direction to the area of the applicator surface.

The invention also resides in various structural improvements in the device by means of which refilling, cleaning and ease of manufacture are accomplished.

Further objects and advantages of the invention will become apparent as the following description proceeds, taken in connection with the accompanying drawing in which:

Figure 1 is a perspective view of an applicator type container (with cap removed) embodying the invention.

Fig. 2 is an enlarged longitudinal sectional view of the device of Fig. 1.

Fig. 3 is an enlarged end view showing particularly the detail of the active end face of the applicator.

Fig. 4 is a plan view, partially in section, of a modified form of applicator type container embodying the invention.

Fig. 5 is a side elevation of the device of Fig. 4, but with the closure cap removed.

Fig. 6 is an enlarged detail view of the active end face of the applicator tip of the device of Figs. 4 and 5.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit

and scope of the invention as expressed in the appended claims.

In the first embodiment of the invention herein illustrated (Figs. 1 to 3) the device is shown as comprising a generally tubular body 10 desirably made of molded plastic or synthetic resin. This body 10 defines a generally cylindrical inner chamber 11 for receiving a reserve supply of lip rouge, unguent or other soft, extrudable material which is to be applied by the applicator. Refilling of the same is facilitated by provision of an applicator tip 12 which is removably threaded to one end of the body 10. When the applicator tip is unscrewed a fresh stick of the lip rouge or the like may be inserted into the chamber 11. A cup-shaped cap 13 is telescoped over the applicator tip 12 and serves to protect the same when not in use. The applicator tip, like the body 10, may be made of molded plastic, while the cap 13 is desirably made as a sheet metal stamping.

Within the chamber 11 is a plunger 14 for expressing the contents of the chamber from the applicator tip. In the present instance the plunger 14 comprises a sheet metal thimble or cup 14a shaped to form a helical thread 14b on its periphery, mating with threads 10a within the member 10. To revolve the plunger 14, for screwing it endwise within the body 10, a cup-shaped finger-piece 15, fashioned as a sheet metal stamping, is provided at the outer end of the body. This finger-piece is revolvably fitted on a reduced end portion of the body 10 and is staked to the outer end of a pin 16 projecting within the body and having a collar 16a rigid therewith for preventing endwise displacement of the pin. A squared shank 16b on the pin projects with a complementary square opening 14c in a disk 14d fixed to the outer end of the plunger thimble 14a. The pin 16 thus has, in effect, spline connection with the plunger so that as the finger-piece 15 is revolved the plunger will be screwed lengthwise within the chamber 11.

The applicator tip 12 itself is of unique construction. In the form shown in Figs. 1 to 3, the tip is of reduced cross-section as compared to the body 10 and tapers gently and smoothly toward its outer end. The active or outer end face 17 of the applicator tip is generally flat and is defined by a plane intersecting the tip at an acute angle with respect to the longitudinal axis of the body 10 and of the applicator tip. Such angular position of the active face of the applicator tip makes it possible to hold the device beneath the mouth while rubbing the surface 17 across the lips, so that the user has a free view of the operation while applying lip rouge or the like to the lips. A plurality of small passages 18, preferably of the order of 0.008 to 0.015 inch in diameter, extend longitudinally through the applicator tip from the chamber 11 to the applicator face 17,

terminating in holes distributed generally uniformly over the latter (see Fig. 3). It will thus be seen that as the plunger 14 is moved toward the applicator tip, it will expel the lip rouge or the like, indicated at 19, in small streams through the passages 18, thus presenting the material for use in metered increments at the applicator face 17.

In order to retain the material 19, in a lateral direction, within the borders of the applicator face 17 and aid in its application, the face 17 is covered by shallow pockets or intagliations. In the device of Figs. 1 to 3 the face 17 is intagliated in a cellular pattern, having therein shallow pockets 17a of generally rectangular form. Preferably these pockets 17a are of a depth of 0.003 to 0.009 inch. The ratio of the width of the pockets to the width of the lands between them may be about two to one and in such case the pockets may be from 0.005 to 0.010 inch on a side, while the lands may be 0.002 to 0.005 inch in width. The suggested dimensions indicate the order of magnitude which is particularly suited for use in applying lip rouge. The cellular pattern of intagliations shown is similar to those used in photogravure etching and, in terms of size for the latter, corresponds to 65 to 130 line screens.

In using the device of Figs. 1 to 3 the cap 13 is removed and the finger-piece 15 turned through a short distance to express a small amount of the material 19 through the passages 18, presenting it at the applicator face 17. The user then wipes the applicator face 17 back and forth across the lips, holding the device like an ordinary crayon type lipstick. As the applicator surface 17 passes across the lips, any excess material is picked up and carried along by the pockets 17a. In this way, smearing or daubing of the lip rouge is prevented, since any of it on the applicator itself is confined within the borders of the surface 17. Consequently, it is possible to paint the material with nicety and precision on the particular area desired and without excessive pressure or rubbing. The intagliated surface 17 smooths and distributes the material evenly over the surface to which it is being applied.

In Figs. 4 to 6 a modified form of device has been shown which embodies the present invention. It differs from the device of Figs. 1 to 3 primarily in that a different form of intaglia has been provided for the active surface of the applicator, and also in that a different form of container, in this case a collapsible tube, is provided. The form of device shown in Figs. 4 to 6 is perhaps better suited to the use of unguents or other medicinal preparations since it embodies a form of container more familiar in merchandising that line of goods and which does not have the artistic appeal of the device of Figs. 1 to 3, the latter being better suited to cosmetics.

In particular, the device of Figs. 4 to 6 comprises a generally tubular body or container in the form of a collapsible tube 20 which terminates in a threaded nipple 21. On this nipple 21 is removably threaded an applicator tip 22, preferably made of molded plastic or synthetic resin. In this instance the applicator tip 22 is of generally cylindrical shape and terminates in an outer or active end face 23 lying at an acute angle to the longitudinal axis of the body 20, just as in the case of the applicator face 17 of the device of Figs. 1 to 3, heretofore described. Within the applicator tip 22 is a central passage 24, registering with the axial passage in the nipple 21, and terminating

in a plurality of small passages 25 that open into the applicator face 23 (see Fig. 6), these passages 25 being of the same order of magnitude, as to size, as the passage 18 heretofore described in connection with the device of Figs. 1 to 3. A friction fitted cup-shaped cap 26 is removably telescoped over the applicator tip 22, to protect the same when not in use.

The face 23 of the applicator tip 22 is intagliated by a plurality of generally elliptical grooves 27 and it will be noted that the passages 25 open into the roots of these grooves. Again, these intagliations or grooves are preferably about 0.003 to 0.009 inch in depth and about 0.005 to 0.010 inch in width. In this instance the lands between the grooves are shown as being approximately equal in width to the grooves. The intagliations or grooves 27 retain the excess material and present it for application in substantially the same manner as that heretofore described in connection with the device of Figs. 1 to 3.

It will be observed that in both of the applicator devices herein described the applicator surface is made of material which will not permanently deform under the pressure normally applied in use so that the user need make no compensation for change in surface contour as would be the case in using an ordinary crayon type lipstick. Since the surface remains fixed in contour and area, the material can be applied with greater precision and definition. In addition, the material being applied can be softer and more plastic than in the case of a crayon type lipstick, since it is supported and retained in position by the applicator itself, so that a lip rouge or the like can be used which adheres more smoothly and evenly to the lips.

I claim as my invention:

1. An applicator type container for soft plastic materials comprising a generally tubular body defining a chamber for retaining a reserve supply of the material, an applicator tip on one end of said body, said tip terminating in an outer end face defined by a plane intersecting the same at an acute angle with respect to the longitudinal axis of said body, said tip having passages therein terminating in a plurality of small openings disposed at spaced points in said face, means including a plunger in said chamber for extruding plastic material from such chamber through said passages, said face of the applicator tip being intagliated throughout substantially its entire area and the intagliations each having abrupt side walls on the sides thereof adjacent the lateral side edges of said end face for shearing off the material as it is pulled from the intagliations upon wiping of said end face from side to side across a surface.

2. An applicator particularly adapted for application of plastic material, with a high degree of precision as to the area covered, to a soft yielding surface such as the lips, comprising a member presenting a generally flat face having passages therein terminating in a plurality of small openings in said face through which the material to be applied may be extruded, and said face being intagliated throughout its entire area with a distribution of the intagliations such that a section normal to the face and in any direction through said member is interrupted by at least one intaglia, and manually operable means for forcing plastic material through said openings.
